UNITED STATES PATENT OFFICE.

BRADLEY DEWEY, OF CAMBRIDGE, MASSACHUSETTS, AND HENRY P. SCOTT, JR., OF WILMINGTON, DELAWARE.

TOP FOR CAN BODIES.

Application filed July 26, 1921. Serial No. 488,183.

To all whom it may concern:

Be it known that we, BRADLEY DEWEY and HENRY P. Scott, Jr., citizens of the United States of America, and residents of Cambridge, in the county of Middlesex and State of Massachusetts, and of Wilmington, in the county of New Castle and State of Delaware, respectively, have invented new and useful Improvements in Tops for Can Bodies, of which the following is a specification.

This invention consists of a new article of manufacture, namely a can top, adapted to be double-seamed to a can body, combined with a sealing - member, deposited on the margin of the can top, the said sealing-member comprising a distributed quantity of individually deformable solid particles, associated with a viscous or colloidal binder. The object of the invention is to provide can tops, ready for attachment to can bodies by the usual process of double-seaming, with a seam sealing member adhesively seamed thereto which comprises an abundant volume of deformable solid materials in comminuted form, capable of flowing between the convolutions of a rolled seam as the seam is formed, completely to fill the irregular voids in the seam.

It has for some time been the practice for can manufacturers, in the manufacture of rectangular, round, or elliptical cans, provided either with solid ends or ends with an opening for a friction cover, to join the ends to the body by means of automatic machinery which rolls or spins the edge of the can cover and the small flange, which has been previously pressed out from the body of the can, into a double seam. Usually some lining compound or a so-called gasket has been employed by the manufacturer to fill and seal the seam made by rolling or spinning the edges of the can end into a fold with the peripheral portion of the can end.

The can manufacturer has habitually furnished to the packers cans with one end double-seamed on, along with died out or stamped can ends to be applied by the packer to the open ends of the can bodies supplied by the can manufacturer. These unattached ends have heretofore been lined around the margin with either a compound or a gasket to give a tight seal when the end is applied to the can-body by the can-

ner. The inherent efficacy of such sealing compounds is of relatively less importance in the can manufacturing establishments where constant skilled supervision is available as well as skilled workmen for constant adjustment of the seamer rolls, than is the case under the imperfect conditions prevailing in many canneries which are in isolated places where skilled mechanics are wanting. There the sealing compounds or gaskets which suffice at the can manufactory frequently fail in their object.

Among the sealing devices which have been employed for the above-mentioned purpose, the principal ones have been gaskets of thin rubber and of unsized paper, and rubber cement solutions squirted into the peripheral groove or curl,—so-called, of the can end.

Rubber gaskets are not only expensive, but involve difficulty in applying to the ends. The paper gasket is also open to the following objections:—

If stamped out of paper which has been imperfectly dried or stored in a humid atmosphere before cutting, the gasket is apt to dry out and shrink so much that it drops out of the can end before the end is rolled onto the can-body. If the paper-lined can-ends are stored in a wet or humid place, such as is frequently encountered in canneries, the paper swells, softens, rolls up during the end-seaming operation, and there results an imperfect, leaky can. If paper-lined can-ends are used in connection with a dry pack where there is no moisture within the can to swell the gasket after the can is done, the seal is often imperfect and pervious to air. Even with packs for which the paper gasket is suited the seams must be very tightly rolled, for otherwise air will gradually seep through and the can will lose its vacuum. Under the best conditions, the paper gasket is incapable of flowing under the local compressions incident to rolling the double seam, and is merely pinched or compressed whenever it lies between the convolutions of metal.

The chief difficulty developed in the use of rubber cement solutions has been that a solution of proper working viscosity is practically limited, as to the amount of rubber content, to about one-half pound of rubber per gallon of solvent. The problem

of which the invention herein described is proffered as a solution, has been to increase the effective volume of the non-volatile portion of the sealing composition, so that enough of such material shall be available to flow into and fill all the interstitial spaces in the rolled seam formed by rolling the metal of the can body and end together. The desirability of providing abundant effective solid filling material for this purpose becomes obvious in the light of the fact that in rolling the metal to form a fold, especially where unskilled attendance is a factor, interstitial spaces between the folds of metal are not perfectly uniform in cross-section. This is conspicuously the case at the point where the side-seam of the can prevents a multiple thickness of the can-metal to be folded into the seam.

20 The sealing member which in combination with a metal can-top constitutes the new article of manufacture herein described is characterized in its broader aspect by the incorporation with a colloidal solution or extension, of comminuted, granulated, or otherwise distributable, deformable solid material. For the purpose here involved, compressibility is the preferred phase or type of deformability. The colloid after evaporation of the solvent or after setting serves to bind the solid components in place, and may also act as a viscous lubricant when the composition is subjected to pressure so that the compressible or deformable solid

30 components, while undergoing deformation by the compressive stresses exerted on it by the formation of close convolutions of metal produced by rolling the can-seam, can flow with the viscous binder. In a narrower aspect, the invention is characterized by a solid material inherently deformable under compression, reduced to small bodies or granules, these granules being bound by means of a viscous colloidal material which

40 fills the voids between the solid granules and constitutes a viscous matrix in which the granules are enclosed and in which as well as with which the granules (each individually compressible or deformable) can flow in response to local inequalities of pressure. Specifically, the invention is exemplified by granulated cork in a solution, highly viscous after setting, or after evaporation of its solvent, preferably and par-

50 ticularly one containing rubber.

We have found other colloidal materials, such as albumen, casein, or glue, suspended in water, effective to form sealing compositions in association with compressible or deformable comminuted solid materials, particularly ground work. Compositions of this character may be flowed or squirted into the "curl" of a can top, there to dry partially, or set, or both, according to the characteristics of the binder.

While it is believed that cork is the material which best exemplifies the inherent compressibility or deformability under compression required as one property of the solid content of the described sealing composition, any solid material which manifests compressibility or deformability in the same or similar manner, may be employed with similar results, provided its surface characteristics are suitable. Particular reference is had to materials such as artificial corks, spongy masses, piths (such as sugar-cane piths), ground balsa wood, leather or other cellular or fibrous bodies, capable of subdivision into individually deformable particles.

A composition which exemplifies this invention may be formed by mixing from three-fourths to one pound of cork, ground to pass forty or fifty mesh, with a rubber solution containing from one-quarter to one-half pound of rubber in one gallon of benzol. This produces a composition containing over five times as much solid material by volume as the thickest rubber solution heretofore commonly used as a can-sealing material. Its solid content is larger than usually necessary for can-sealing purposes, so that the packer may safely thin it by the addition of some benzol to a consistency which he finds suitable to the conditions under which he operates.

A sealing composition of the usual rubber solution type is commonly colored with pigments or spirit-soluble dyes in order to facilitate inspection of the lined ends for skips or smears. In compositions made under this invention any suitable coloring may be incorporated as heretofore, but because of the greater volume of solid residue deposited when the solution sets or loses the volatile solvent and because of the opacity of the cork or other compressible or deformable material, this coloring, which is oftentimes an expensive component, is not required.

When such a rubber solution and ground cork composition is flowed or squirted into the curl of the can top, and the solvent evaporates in large part, the adhering residue may have a cracked, porous or lace-like surface. It is, however, soft and moldable under pressure, and when the can seam is rolled, the ground cork squeezes and flows in and with the binder into all parts of the interstitial spaces of the seam entering into and completely filling the larger voids in response to the relatively high pressures developed where the metal surfaces are pressed more closely together. Although at the start the adhering residue is apparently non-homogeneous, the pressure and flow under the double seaming operation usually results in the formation of two separate continuous ribbons of compound on each side of the folded-in portion of the body of the can.

It has been discovered upon close inspection that when the composition herein described comprising rubber solution as the viscous binder with cork, is used for sealing a can, the predominance in quantity of cork over rubber enables a can containing oil, paints, or solvents which attack rubber to remain tight nevertheless and furthermore that it prevents any oozing of the compound when the cans are processed.

A sealing composition, as described in this specification, may be supplied in the form of a slightly viscous solution ready to be applied to the ends substantially according to any of the methods now in common use, or may be supplied in the form of a very viscous solution or concentrated dough, which may be applied to the can ends while of that consistency, by scraping from a roller or by extrusion or any other suitable means, or may be thinned by the addition of solvent to a consistency where it can be flowed or squirted on to the can-ends.

In the drawings herein annexed, which illustrate the invention,—

Figure 1 is a plan view of a can-end, with the sealing member adhesively attached;

Figure 2 is a section, at the line 2—2 of Figure 1, showing part of the metal can-top and the sealing member, on a larger scale; and

Figure 3 is a section of a rolled can seam, on still larger scale.

In the drawings, T represents a round can top with a small inturned peripheral flange C, called the "curl". S represents

the sealing composition member, adhesively deposited around the margin of the can top, next to and within the curl C.

In Fig. 3, the convolutions of metal of 40 which the can top T and body B are composed, are shown in section at the rolled double seam. The sealing member, under the heavy compression produced where the metal flanges are rolled into close contact 45 shows in the interspaces or voids at S, with which the solid deformable particles and the viscous binder have flowed, being intruded thereto by the pressure exerted at other points.

We claim:

1. A can top, adapted to be double-seamed to a can-body, having a sealing member comprising individually deformable solid particles in association with a viscous 55 binder, adhesively deposited on its margin.

2. A can top, adapted to be double-seamed to a can-body, having a sealing member comprising individually deformable solid particles in association with rubber, 60 adhesively deposited on its margin.

3. A can top, adapted to be double-seamed to a can body, having a sealing member comprising cork particles associated with rubber, adhesively deposited on its 65 margin.

Signed by me at Cambridge, Massachusetts, this 20th day of July, 1921.

BRADLEY DEWEY.
